Lazarus C. Martin

By his Attorneys,

Chas. Snow & Co.

UNITED STATES PATENT OFFICE.

LAZARUS C. MARTIN, OF GREENCASTLE, PENNSYLVANIA.

CAR-COUPING.

SPECIFICATION forming part of Letters Patent No. 485,829, dated November 8, 1892.

Application filed March 8, 1892. Serial No. 423,616. (No model.)

To all whom it may concern:

Be it known that I, LAZARUS C. MARTIN, a citizen of the United States, residing at Green-
castle, in the county of Franklin and State of
Pennsylvania, have invented a new and use-
ful Car-Coupling, of which the following is a
specification.

The invention relates to improvements in
car-couplings.

10 The object of the present invention is to
simplify and improve the construction of car-
couplings and to provide one which may be
readily operated from the sides or the top of
a car, thereby obviating the necessity of per-
15 sons going between cars and greatly facilitat-
ing the making up of trains.

The invention consists in the construction
and novel combination and arrangement of
parts hereinafter fully described, illustrated
20 in the accompanying drawings, and pointed
out in the claim hereto appended.

In the drawings, Figure 1 is a perspective
view of a car-coupling constructed in accord-
25 ance with this invention. Fig. 2 is a longi-
tudinal sectional view. Fig. 3 is a transverse
sectional view.

Like numerals of reference indicate corre-
sponding parts in all the figures of the draw-
ings.

30 1 designates a draw-head having a flaring
mouth 2 and having journaled transversely
of it a rock-shaft 3, which is provided at its
middle with a depending link-engaging arm
4, arranged within the longitudinal opening
35 of the draw-head, formed by a bend of the
rock-shaft. The arm 4 of the rock-shaft is
held in a vertical position against a shoulder
6 of the bottom of the draw-head by a spiral
40 spring 7, which is disposed on the rock-shaft
and is arranged in one of the bearing-open-
ings of the draw-head. The said arm 4 is
adapted to be forced rearward against the
action of the spring by a link 8 when two cars
45 come together, thereby coupling the cars au-
tomatically. The uncoupling of the cars may
be performed at the sides of a car by turning
handles 10 at the ends of the rock-shaft and
from the top of a car by a rod 11, provided at
its upper end with a handle and having its
50 lower end connected with a rearwardly - ex-
tending horizontally-disposed arm 12 of the
rock-shaft.

Should it be desirable to couple a car hav-

ing the improved coupler-head with a car hav-
ing one of the ordinary construction, it may 55
be readily done by simply engaging the link
with the arm 4; but the draw-head 1 is pro-
vided with a pin-opening 14, in which is ar-
ranged a coupling-pin 15, adapted to be used
in case the arm of the rock-shaft should be 60
come broken or the coupling be rendered tem-
porarily defective from some other cause.

It will be seen that the car-coupling is sim-
ple and comparatively inexpensive in con-
struction and that the operation of coupling 65
and uncoupling may be readily performed
from the top or at the sides of the car and
without necessitating a person going between
cars and that shifting of cars and making up
of trains is greatly facilitated. It will also be 70
seen that should the coupling become injured
in any manner the ordinary pin-and-link coup-
ling can be employed.

The flaring mouth of the draw-head enables
cars having draw-heads at different heights 75
to be readily coupled without employing other
link-lifting mechanisms, as a link will be
guided by the bevel or incline of the mouth
of the draw-head into the opening thereof.

What I claim is—

In a car-coupling, the combination, with an
ordinary link, of a draw-head having a longi-
tudinal opening and provided with a shoul-
der at the bottom of the same and having a
coupling-pin perforation arranged in rear of 85
and close to the shoulder, whereby the point
of engagement with a link will always be at
the same point, a rock-shaft journaled in the
draw-head and provided with a central de-
pending link-engaging arm formed by a bend 90
of the rock-shaft and arranged within the
opening of the draw-head and adapted to bear
against the shoulder thereof, a spring holding
the arm in engagement with the shoulder,
handles arranged at the ends of the rock-shaft 95
and located at the sides of a car, and a rod
designed to extend to the top of a car and
connected with the rock-shaft, substantially
as described.

In testimony that I claim the foregoing as 100
my own I have hereto affixed my signature in
the presence of two witnesses.

LAZARUS C. MARTIN.
